UNITED STATES PATENT OFFICE.

ERIK ARTUR FAGERLUND AND ARVID ADOLF HERIBERT BÖRJESON, OF STOCKHOLM,
SWEDEN, ASSIGNEES OF ONE-HALF TO GUSTAF SVALLING, OF STOCKHOLM, SWEDEN.

CLEANING-MACHINE FOR DISHES AND SIMILAR ARTICLES.

1,139,406.

Specification of Letters Patent. Patented May 11, 1915.

Application filed July 9, 1914. Serial No. 850,042.

To all whom it may concern:

Be it known that we, ERIK ARTUR FAGERLUND and ARVID ADOLF HERIBERT BÖRJESON, both subjects of the King of Sweden, and 5 citizens of Sweden, residing, respectively, at Malmtorgsgatan 3 and Svedenborgsgatan 2, Stockholm, in the Kingdom of Sweden, have invented certain new and useful Improvements in Cleaning-Machines for 10 Dishes and Similar Articles, of which the following is a specification.

The present invention relates to such cleaning machines, in which the articles to be cleaned, are arranged on a conveyer, moving 15 between brushes.

A machine according to the present invention is essentially characterized by two adjacent brushes, without entering into each other, being placed in such relation to the 20 conveyer, that the bristles on both brushes or only on one of them project through the conveyer.

Another feature of the present machine consists therein, that above one brush or a 25 number of brushes, placed below the conveyer, there is placed a pressure member, which as the articles to be cleaned are passing below it acts to hold said articles pressed against the conveyer.

30 Further the present machine is characterized by the fact, that the articles to be cleaned after having passed the cleaning device in one direction, pass through a washing device in the opposite direction.

35 A machine according to the present invention is shown in the accompanying drawing.

Figure 1 is a side elevation of the machine. Fig. 2 is a cross section; Fig. 3 a 40 plan view thereof, and Fig. 4 is a plan view of the presser member.

a indicates an endless conveyer, on the upper part of which the articles to be cleaned are placed. This conveyer is driven 45 in the direction indicated by the arrow in Fig. 1. *b* indicates another endless conveyer, arranged laterally of the conveyer *a* in an inclined position, so that only its one end, the delivering end adjacent to the 50 receiving end of the conveyer *a* reaches with the upper part into the same plane as the upper part of the conveyer *a*. Both conveyers are mounted in the same tank *c*, which is filled with water. From the delivering

end of the conveyer *a* an inclined plane *d* 55 extends down to the receiving end of the conveyer *b*, which is located near to the bottom of the tank.

According to the embodiment shown on the drawing, the machine is provided with 60 three brushes *e*, *f*, *g*, which are rotary mounted. A brush *e* is mounted above the conveyer *a*, while the two other brushes *f*, *g* are located on each side of the brush *e* below the upper part of the said conveyer in 65 such manner, that the bristles thereof project through the upper part of said conveyer without entering into the bristles of the upper brush *e*.

The conveyers *a* and *b* consist, according 70 to the drawing, of ropes or chains *i*, provided with hooks *l*, which have for their purpose to prevent a displacement of the articles to be cleaned in respect to the conveyers, in which said articles are placed. 75 The driving of the brushes and conveyers is effected by means of suitable chain transmissions and toothed gearings.

The articles to be cleaned are placed on the conveyer *a* on the right hand end thereof (Fig. 1), and are brought, by the said conveyer to pass between the brushes, so that they are thoroughly worked by these latter, and said articles are then delivered, at the left hand end of the conveyer, upon 80 the incline *d*. On this incline the things slide downward upon the left hand or lower end of the conveyer *b*, which is driven in opposite direction to the conveyer *a*, so that the articles on the conveyer *b* are carried 85 back to the right hand end of the machine, and in flush with the upper part of the conveyer *a*. During this passage upward through the tank filled with water, the articles are 90 completely washed.

Above the lower brushes or one of them there is arranged a pressure member *m*, which is pivoted to the frame of the machine with its one end, and which acts by 95 its gravity to press upon the article passing below it, so that such article is held against the conveyer and thereby is properly worked by the brush.

Having now particularly described the nature of our invention and in what manner 105 the same is to be performed, we declare that what we claim is:

A dish washing machine comprising in

combination a tank, a conveyer movably mounted in said tank, cleaning elements mounted in said tank, positioned above and below said conveyer and at least one of 5 said elements extending through said conveyer, retaining members secured to said conveyer and a presser member mounted for vertical movement with respect to said tank engaging one of said elements, serving to force the dishes carried by said con-

veyer against said cleaning element, substantially as described.

In testimony whereof we have affixed our signatures in presence of two witnesses.

ERIK ARTUR FAGERLUND.
ARVID ADOLF HERIBERT BÖRJESON.
